HOLDERS FOR PRESSURE-ACTUATED CANISTERS

Max Dickman, Philadelphia, Pa.

Application May 25, 1955, Serial No. 510,881

2 Claims. (Cl. 222—323)

The object of the invention is to provide improvements in holders for pressure-actuated canisters, and especially in a holder for such canisters that embodies a handle that in general follows in shape and inclination of the hand-grip of certain automatic firearms, which as the result of long use under every known condition has proved to be the most accommodative to one's hand when aiming such firearm, and likewise the discharge on fire of a pressure canister; also means to removably or detachably secure to said hand-grip canisters of widely varying sizes; and a triggerlike lever by which movement of a finger of the operator is adapted to depress the spring-positioned plunger of such a canister, and thereby release therefrom as much as may be desired of its contents.

Another and more specific object is to provide a device of this type, which comprises a hand-grip of the simplest form that can be produced upon moulding and rabbeting machines, and which is provided with a longitudinally extending groove, in which is pivotally secured a lever of which one end serves as a manually actuatable trigger, while the opposite angularly related portion extends into the proximity of and is adapted to engage and depress the spring-positioned plunger of the type of canister in question, for as long as it is desired that its contents shall be dispensed therefrom in a jet or stream of atomized particles.

A further object is to provide in such a device a supporting element for a canister, which comprises in general a plate that is bifurcated at one end to receive between its spaced arms a portion of said hand-grip, while its opposite end portion is bifurcated to provide a pair of oppositely curved arms, adapted to yieldingly grip the upper portion of a canister, and operatively maintain such upper portion in suitable close proximity to the plunger-engageable end of said lever, while between said first-mentioned pair of arms said element is provided with a central portion, that normally enters a recess of corresponding shape in said hand-grip, and thereby cooperates with a pivot securing said first arms to said hand-grip to prevent angular movement of said element with respect to said grip.

Still another object is to provide a modified form of the device, which comprises a plate having an elongated aperture of generally figure 8 shape, the larger end portion of which is adapted to pass the uppermost closure (or other desired) portion of a canister, while following such closure portion having been shifted into the smaller portion of said aperture, it is fixedly though removably secured therein as by frictional engagement with the sides of said smaller portion, and the intermediate portion of said aperture between said one portions functioning to sufficiently restrict the entrance to said smaller portion, as to resist the accidental removal of said canister therefrom, said plate being secured to a suitable handle-grip, and a lever being also provided by which the exit orifice control of the canister is actuated against internal pressure to release the contents of said canister when and to the extent desired.

And a still further object is to provide a further slightly modified form of the device, which comprises a plate having a generally circular aperture, whose periphery is interrupted by a pair of radial cutouts, through which 5 radial projections from a canister may pass, as the adjacent portion of said canister passes through said aperture, following which upon turning the canister as with a bayonet lock said projections are shifted into positions above the uninterrupted portions of said aperture, where 10 there are preferably yieldingly maintained by said projections sinking into slightly depressed diametrically related surface portions of said plate adjacent to said aperture.

With the objects thus briefly stated, the invention comprises further details of construction and operation, which 15 are hereinafter fully described in the following specification, when read in conjunction with the accompanying drawings, in which Fig. 1 is a side elevation of a device comprising one embodiment of the invention, operatively attached to and supporting a pressure-actuated canister containing paint or other fluid; Fig. 2 is a plan view of the canister-supporting element per se; Fig. 3 is a top plan view of the composite device shown in Fig. 1; Fig. 4 is a vertical longitudinal section of the same; Fig. 5 is a transverse section of the same on the line 5—5 of 25 Fig. 3, showing the form of frictional gripping engagement of the upper end portion of a canister by the outer arms of said element; Fig. 6 is a side elevation of a simplified modification of the basic invention; Fig. 7 is a top plan view of the same; Fig. 8 is an enlarged plan view of 30 the supporting plate per se; Fig. 9 is a plan view of the free end portion of a modified form of said plate; Fig. 10 is a plan view of the upper portion of the canister that is designed for use with said last-mentioned form of said plate; Fig. 11 is a longitudinal vertical section of said 35 plate on the line 11—11 of Fig. 9, and showing the upper portion of the canister of Fig. 10 in operative association therewith; and Fig. 12 is a vertical diametrical section through a well known type of canister construction such as that represented by and disclosed in United 40 States Patent No. 2,777,735.

Referring to Figs. 1 to 5 of the drawings, a simple and highly satisfactory handle, or hand-grip 1 is shown as comprising an elongated piece of wood, plastic, or other suitable material, that is provided, in its forward portion with an upwardly extending slot 2 normally directed away from the operator, and which grip preferably slopes upwardly and forwardly to conform as nearly as possible to the natural direction or position of the palm of the hand, as when gripping a firearm or the like and complete naturalness is required. The upper and lower ends of this hand-grip may be horizontal or otherwise as preferred.

Within the upper portion of said slot is pivotally secured an approximately central intermediate portion 35 of a lever, that essentially comprises an upper forwardly projecting actuating arm 4 and a generally downwardly extending trigger arm 5. The pivotal mounting is maintained by means of a transversely extending rivet 6 or the like, while the trigger arm of said lever is free to swing, 40 from an inoperative position beyond the transverse limits of said slot 2, to a retacted position more within yet not wholly sheltered by the sides of said slot, as when it is forced rearwardly by manual pressure of a finger of the operator, while his hand surrounds said grip as a handle.

For operatively supporting a canister in fixed relation to said handle-grip, a supporting element is provided that essentially comprises a bifurcated rear end portion secured to said grip, and a bifurcated forward portion characterized by resiliently positioned arms, to yieldingly receive a convenient portion of a canister, as indicated in Fig. 1. Said supporting element may be a pair of properly spaced stiff wire members or the like, but

is here shown as comprising a plate 7, whose rear end is bifurcated to provide a pair of upwardly directed parallel flanges 8 between which the upper portion of said grip is positioned slightly beneath the level of the rivet 6, and secured together in fixed relation by means of a single rivet 9.

Between said flanges the intervening rearwardly directed edge of said plate is provided with a preferably flat portion 10, that is positioned in a transversely extending slot 11 in said grip, and which tongue in indirect cooperation with said last-mentioned rivet fixedly maintains said grip and said plate in predetermined angular relation. The forward portion of said plate is bifurcated to provide a pair of resiliently positioned slightly arcuate arms 12, which in cross section are flanged at 8' to increase their vertical rigidity and which makes them of generally L-shaped cross section, the lower flanges of which lie in a common plane and normally enter the vertically narrow, circumferentially extending groove 13, that inevitably occurs at the junction of the closure 14 with the uppermost, inwardly sloping, slightly conical top wall 15 of said canister, beneath which said canister may be of any convenient shape, but which is here shown for example, as comprising a lower cylindrical portion 16, closed at its bottom 17, and merging into an abbreviated upper cylindrical portion 18 by means of an intermediate conical section 19. Resilience of the arms of the forward portion of said plate may be increased by providing a V-shaped cutout 20 as indicated in Fig. 1.

Such a canister contains any one of various kinds of fluids under pressure, and which fluid is adapted to be discharged in a gradually expanding spray 20' from an orifice 21, that is directed laterally from a centrally positioned, upwardly directed plunger 22, against or closely adjacent to which the free end of the lever arm 4 is normally positioned. With the several elements and their respective parts positioned as shown in Fig. 1, and the hand of the operator firmly grasping the handle-grip, rearward movement of the trigger portion of said lever into the slot 11 causes said lever to depress said plunger, and while thus under perfect control permit just as much or as little of the canister's content to be ejected from said orifice as may be desired.

Referring to Figs. 6, 7 and 8, a slanting rectilinear handle-grip 25, has secured to it by means of a rivet 26 a pair of rearwardly directed spaced parallel ears 27, that comprise integral extensions of a substantially horizontally positioned plate 28, which is transversely stiffened by a peripherally extending flange 29, that comprises a generally U-shaped continuation of and which connects said ears. The forward portion of said plate gradually widens from said ears to form an intermediate portion 30 and a freely extending terminal portion 31, in which is a generally 8-shaped aperture, that comprises a rearwardly positioned larger portion 32, a forwardly positioned smaller portion 33, and an intervening slightly constricted portion 33'.

A canister 34, having an upper circular closure 35 providing a slightly undercut annular recess 36, is attached to said plate by first inserting said closure through the larger rear portion of said aperture, and then either by a direct rectilinear or rotary motion is forced past an intermediate constricted portion 33' of said aperture, until the recess 36 of said canister receives the circular edge of the smaller portion of said aperture. The laterally opposite sides of said plate in the vicinity of said constricted portion are sufficiently resilient to expand or separate enough to pass said closure recess surfaces, and then contract and yieldingly secure said canister in fixed operative position with relation to said plate and thereby with said handle-grip as well.

The rearmost horizontal portion 37 of said plate is tightly lodged within a sawcut or the like 38 in said handle-grip, so that in conjunction with the rivet 26 said

plate and said grip are normally secured in fixed angular relationship. The intermediate portion 30 of said plate is provided with an upwardly deflected ear 39, to which by means of a rivet 40 there is pivotally secured thereto the central portion 41 of a lever that essentially comprises a depending trigger portion 42, and a forwardly projecting actuating portion 43, whose outer free end normally terminates either close to or preferably in light contact with a flow-controlling plunger 44 of said canister, said plunger being provided with an orifice 45 from which fluid within said canister is adapted to be discharged in a gradually expanding stream or jet 46. Normally, the trigger portion of said lever is in spaced angular relation to said handle-grip, so that when it is drawn rearwardly by a finger of the operator when grasping said grip, the said plunger is depressed and liquid or fluid as the case may be is released as indicated.

Referring to Figs. 9, 10 and 11, it will be understood that the fragmentary portion of the canister-supporting plate here shown is a modification of the corresponding portion of the plate shown in Figs. 6-8, with the same handle-grip and actuating lever hereinbefore described being used with it. Said plate 28 is provided with the same marginal stiffening flange 29, while instead of the 8-shaped aperture there is provided a circular aperture 50, having diametrically positioned radially projecting enlargements or offsets 51, while circumferentially between said offsets there are positioned diametrically related depressed recesses 52. The radially enlarged annular periphery 53 of the closure of a canister 54 is provided with diametrically related, radially projecting lugs 55, which are adapted to pass through the enlargements 51 as said closure passes through said aperture, after which said closure can be rotated until its lugs are in alignment with and fall into said recesses, whereupon whatever form of actuating lever level may be present is operative to depress the orifice-controlling member 56, as before described. Removal of said canister and its closure from said plate is accomplished by reversing the rotation of the former, until its said lugs are free to be withdrawn through said offsets and said closure from said aperture.

Illustrating the well known construction and operation of the valves present in such canisters as those herein referred to, reference is made to United States Patent No. 2,777,735, whose Fig. 2 is here reproduced as Fig. 45 12 and which shows the general mounting of a valve head 22-44-56, that corresponds with the respective valves 22, 44, 56 hereinbefore referred to. The essential elements of such a valve and adjacent parts 50 comprise the usual upper wall 60 of the closure of the usual canister, having a central upwardly projecting cylindrical extension 61, topped by a wall 62 having a central port 63, through which slidably reciprocates a tubular valve stem 64, that communicates with an internal bore 65 in said valve head, and from the upper portion of said bore leads a generally horizontally extending discharge bore and orifice 21-45. The lower end portion of said valve stem is provided with elongated ports 66 below a resilient packing washer 67 that seals the upper port 63, 60 while its lower end is closed by a polygonal cap 68, that limits the effective vertical length of the ports 66 and at the same time serves as a guide in slidable engagement with the interior of a depending cylindrical casing 69, whose uppermost outwardly flanged portion 70 is secured 65 between the packing washer 67 and a suitable annular shoulder upon the inner surface of the upward canister extension 61. The under side of said cap 68 is provided with a cross slot 71 and rests upon the upper end of a depending tube 72, that is secured in the lower restricted 70 end portion 73 of said casing, while a coil spring 74 encircles said casing and normally forces said polygonal cap 68 upwardly against the under side of said packing washer, so as to thereby normally prevent the passage of the canister's contents into and from the valve head 75 22-44-56, after passing said polygonal cap. By such a

construction manually drawing the trigger 42 towards the handle-grip 25, for example, causes the trigger's actuating portion 43 to depress said valve head and thereby the stem 64 and cap 68, so that the internal pressure of the canister is free to force its contents from the discharge orifice, as hereinbefore described.

Having thus described my invention, what I claim and desire to protect by Letters Patent of the United States is:

1. A manual holder for canisters containing fluids under pressure that have a closure top and also have a discharge orifice in said closure top controlled by a member that is normally yieldingly positioned, comprising a handle-grip, a plate fixedly secured to and forming a forward extension of said handle-grip, said closure top on said canister forming with said canister an intervening annular groove said plate being provided with an elongated aperture of which one end portion is sufficiently large to pass the closure while its opposite end portion is adapted to at least one-half encircle the annular groove, and the intermediate portion of said aperture being sufficiently constricted to prevent the accidental escape of said closure from the smaller end of said aperture, and a lever having an intermediate portion pivotally secured to said handle-grip, while one of its ends extends in variably close proximity to said handle-grip to form a trigger, and the opposite end extends into operative relation with the orifice-controlling member of said canister, to release the contents when said trigger is shifted.

2. A manual holder for canisters containing fluids under

pressure that have a closure top and also have a discharge orifice in said closure top controlled by a member that is normally yieldingly positioned, comprising a handle-grip, a plate secured at one end to and forming a unitary forward extension of said handle-grip, a closure on said canister forming with said canister an intervening annular groove said plate having a peripheral flange to stiffen it transversely and an elongated substantially 8-shaped aperture of which one end portion is sufficiently large to pass the closure of a canister while its other end portion is adapted to at least one-half encircle the annular groove beneath such closure, and the intermediate portion of which aperture being sufficiently constricted to prevent the accidental escape of such canister from the smaller end of said aperture, and a lever having an intermediate portion pivotally secured to an ear carried by said handle-grip, while one of its ends extends in variably close proximity to said handle-grip to form a trigger, while the opposite end extends into operative relation with the orifice-controlling member of said container, to release the contents when said lever is shifted.
